UNITED STATES PATENT OFFICE.

CLARENCE R. WELCH, OF SCRANTON, PENNSYLVANIA.

CONTROLLING APPARATUS FOR HOISTING-ENGINES.

1,150,720.

Specification of Letters Patent. Patented Aug. 17, 1915.

Application filed July 9, 1913. Serial No. 773,204.

To all whom it may concern:

Be it known that I, CLARENCE R. WELCH, a citizen of the United States, residing at Scranton, in the county of Lackawanna and 5 State of Pennsylvania, have invented new and useful Improvements in Controlling Apparatus for Hoisting-Engines, of which the following is a specification.

The present invention has reference to 10 controlling apparatus for hoisting engines, and more especially to apparatus of the general type shown and described in my prior Patent Number 965,779, granted July 26, 1910. It proposes certain hereinafter described improvements in or relating to the 15 trip mechanism and the actuating means therefor, the construction and arrangement of the instrumentalities specified being such as to insure an automatic setting of the 20 brakes under predetermined conditions.

An embodiment of the invention is illustrated in the accompanying drawing, whereof:—

Figure 1 is a plan view showing the application 25 of the improved controlling apparatus to a hoisting engine; Fig. 2 is an enlarged side elevation of the controlling apparatus, with the parts thereof in normal position; Fig. 3 is a similar view of the 30 primary trip-actuating device and its operating mechanism, but showing the position of the parts after operation; Figs. 4 and 5 are side elevations of the two secondary trip-actuating devices and the operating mechanism 35 thereof, likewise showing the position of the parts after operation; and Fig. 6 is an enlarged detail plan view of one of the aforementioned secondary trip-actuating devices and the element which directly operates 40 the same.

In said drawing, 1 indicates, generally, the drum element of the hoisting engine, 2 the brake mechanism associated therewith, and 3 the mechanism for controlling the operation 45 of the brakes. The drum and its brake mechanism may be of any preferred or conventional type, and, therefore, require no extended description. The controller 3 is preferably similar, in the main, to that shown in my prior patent, above identified, and, like 50 the parts 1 and 2, is here represented as of duplex character; that is to say, the two brake levers 4 have separate connections 5 with the brakes that act upon the two drum sections, and each of these levers is also connected to a piston 6 which works within a

cylinder, motive fluid being supplied to said cylinders through the pipe line 8, so that when the pistons are driven outward by the entrance of the fluid into their respective 60 cylinders, the levers connected thereto will be forced backward, thereby applying the brakes.

In the preferred form of apparatus, mechanism is employed for automatically controlling the operation of the valve system which, in turn, controls the passage of the motive fluid to the cylinders, when the cage approaches either end of its travel in the elevator shaft, or the like, and, also, at any 65 intermediate point in such travel when the speed at which the engine is running becomes excessive. As in the earlier construction, this mechanism is of the trip type, but it is simplified both as to the number of its 70 parts and as to its actual operation. Accordingly, while two trips are employed, one of these trips is actuated both when the cage approaches one end of the shaft and, also, when the speed of the engine reaches 75 the danger mark, so that it serves as a combined terminal and speed trip, the other trip being actuated when the cage approaches the opposite end of the shaft. These trips are indicated by the numerals 9 and 10, and, as 80 shown in Figs. 3 and 4, are preferably substantially angular or L-shaped. They are pivoted adjacent their apices to a pair of brackets 11 which are fastened to the main standards 12, or in any other desired manner, and are designed to directly control the aforementioned valves, two of which, indicated by the numerals 13 and 14, are comprehended in the valve system, through the agency of a pair of bars 15 and 16 pivotally 85 connected at one end to upstanding arms 17 and 18 attached to the pipe line. These 90 valves are located in the two inlet sections of the pipe line, as will be understood, and are normally held open by means of springs 19 and 20 which act upon the valve stems, the closing of the valves and their retention in such position being effected by the engagement of the hooked upper ends 21 and 22 of the vertical arms of the trips with the 95 free ends of the bars 15 and 16, said bars extending across the headed upper ends of the 100 valve stems.

To release the trips from engagement with the valve-operating bars 15 and 16, 105 primary and secondary devices, hereinafter described, are made use of, one of the sec-

ondary devices actuating the trip 9, while the other secondary device and the primary device both serve to actuate the trip 10. Referring to Figs. 1 and 2, it will be seen that the drum shaft 23 has a chain-and-sprocket, or other suitable connection 24 with one end of the upper of a pair of parallel horizontal shafts 25 and 26 which are journaled in the standards 12. This shaft 25 is threaded and carries a traveling collar 27 which is straddled by the legs of a bifurcated nut 28 mounted on the lower shaft 26, said legs having openings through which shaft 25 loosely passes. Collar 27 has a key-and-groove connection 29 with shaft 25 to insure its rotation therewith and movement endwise thereon, and is also provided with a laterally-projecting peripheral finger 30 that serves to operate either of the secondary trip-actuating devices, according as the compound part 27-28 is traveling in one direction or the other on the shaft 25. These two devices are indicated by the numerals 31 and 32, and are preferably in the form of slides that are mounted in recessed guide brackets 33 connected to the standards 12. At their front ends, these slides are provided with hinged sections or members 34 and 35, which are formed with three steps of different lengths, as shown in Fig. 6, for engagement by the finger 30 on collar 27. The rear or outer ends of the slides are pivotally connected to a pair of links 36 and 37 that are connected, in turn, by a second pair of links 38 and 39, to a pair of crank arms 40 and 41 secured to a horizontal rock shaft 42, the latter being journaled in standards 12 above and parallel with the threaded shaft 25.

Considering so much of the apparatus as has already been described, it will be understood that shaft 25, owing to its connection with the drum shaft, will rotate at a speed directly proportional to the speed at which the cage (not shown), travels in the elevator shaft, and for this reason the position of the traveling collar 27 upon shaft 25 will correspond to that of the cage in the elevator shaft. The two slides 31 and 32 project toward shaft 25 and are disposed adjacent the ends thereof, with the longest steps on their hinged sections 34 and 35 in the path of movement of the finger 30 on collar 27. Consequently, since the aforementioned collar travels backward and forward on shaft 25 and is caused to rotate during such travel, its finger will engage and lift the section 34 at approximately one end of its travel, and, similarly, the section 35 at approximately the other end of its travel. The lower arms of the trips 9 and 10 project downwardly at an angle and terminate directly over the said sections, so that when either section is raised, it will rock the adjacent trip upon its pivot and

thereby disengage its hooked end from the corresponding valve-operating bar, whereupon the valve controlled thereby will immediately open, with the result that motive fluid will be free to flow through the pipe line to the cylinders 7. Pistons 6 will then operate to shift the brake levers 4 and set the brakes, this braking taking place automatically, as will be apparent, just about or shortly before the time that the cage reaches either end of the shaft.

It is to be observed that the aforementioned application of the brakes is effected at the end of each ascent or descent of the cage, and under normal conditions,—that is to say, when the engine is running at normal speed,—but it is also intended to effect the same operation automatically at any intermediate point in the travel of the cage when the speed of the engine rises beyond a predetermined figure. The primary, or speed trip-actuating device, is operated for this purpose, and, as previously stated, that device acts upon the trip 10, which is also released by the secondary device 32. The device in question is preferably constituted by a projecting finger 43, or the like, which is located directly in line with the upper arm of the trip 10 and is carried by a horizontal rock shaft 44 controlled from the governor 45. Shaft 44 is journaled in a bracket 46 fastened to the pipe line, as shown in Fig. 1, and has attached to it a crank arm 47 which is connected by a link 48 to a crank arm 49 secured to rock shaft 42, so that the operation of the latter shaft will effect that of shaft 44.

The governor 45 is preferably of the form shown in Fig. 3, and embodies a vertical sleeve-like hollow shaft 50 contained within a fixed sleeve 51 that is mounted upon a stand 52, the shaft 50 having a gear connection 53 with a horizontal transmission shaft 54 which, in turn, has a chain-and-sprocket connection 55 with the rear end of the threaded shaft 25. Shaft 50 also carries the weighted governor arms 56, the latter acting directly upon the headed upper end of a vertical rod 57, which is loosely fitted within said shaft. This rod is normally held in raised position by suitable mechanism, here shown as comprising a lever 58 that is fulcrumed intermediate its ends upon a bracket 59 mounted on stand 52, the lower end of the rod resting upon one arm of the lever, while the other end thereof carries a weight 60. The latter arm is further provided with a forked terminal 61 which straddles the reduced upper portion 62 of a post 63, said reduced portion having slidably fitted thereon a weight 64 that also engages fork 61. Consequently, when the engine is running at a normal speed, the combined action of the two weights 60 and 64 will maintain the adjacent arm of lever 58 depressed,

with the fork 61 resting upon the shoulder produced by the reduction of the part 62, while the other arm of said lever, and, therefore, the rod 57, will be elevated. On the other hand, when the speed of the engine becomes excessive, the outward movement of the weighted portions of the governor arms 56 will cause their inner portions to depress rod 57, with the result that the corresponding lever arm will be forced downward from the position represented in Fig. 2 to that in Fig. 3.

As previously stated, the rock shaft 44 is controlled from the governor 45 through the intermediary of the rock shaft 42, the crank arms 47 and 49, and the connecting link 48. Shaft 42 is, accordingly, itself connected to said governor to effect such control, the connection consisting of a link 65 which is attached at one end to the inner arm of lever 58, *i. e.*, the opposite arm from that which carries the weight 60, and a crank arm 66 that is secured to shaft 42 and is connected to the other end of link 65. By reason of this construction and arrangement of parts, it will be apparent, therefore, that when the speed of the engine is sufficiently high to effect the rocking of the controlling lever 58, the depression of the working arm of that lever will produce a counter-clockwise movement of shaft 42 through the parts 65 and 66 and such movement will be transmitted through the parts 49, 48 and 47 to shaft 44. The shaft last mentioned will be turned in a clockwise direction, which will cause its finger 43 to bear against trip 10 and thereby disengage the latter from bar 16, whereupon valve 14 will immediately open to permit the motive fluid to set the brakes.

Accordingly, it is to be understood, so far as the complete operation of the apparatus is concerned, that under normal conditions the brakes will be set automatically when the cage reaches approximately either end of the shaft, and that when the engine rotates at a dangerously high speed, the brakes will be set automatically by the operation of the primary trip-actuating device, irrespective of the position of the cage in the shaft. In the same connection, it is to be noted, however, that the main rock shaft 42, which is actuated from the governor, is connected with the two secondary trip-actuating devices 31 and 32, the former through the parts 36, 38 and 40, and the latter through the parts 37, 39 and 41. Consequently, when the shaft 42 is rocked, the parts just referred to will cause the said devices 31 and 32 to move toward shaft 25, and this will obviously result in bringing the hinged sections 34 and 35 nearer to the finger 30 on collar 27, so that the short or narrow steps on either of said sections will be in position to be struck and lifted by said

finger if said collar happens to be at such times opposite that section. In this way, the application of the brakes is insured, since, under the conditions specified, both the primary trip-actuating device and one of the secondary trip-actuating devices will be operated.

What is claimed is:

1. In an engine controlling apparatus, the combination of a rocking trip; a rock shaft 75 having a finger thereon arranged directly adjacent said trip and adapted to engage the same; a governor; and connections between said governor and said shaft for rocking the latter from the former to cause 80 said finger to press against and actuate said trip.

2. In an engine controlling apparatus, the combination of a rocking trip; a primary trip-actuating device comprising a rock 85 shaft having a finger arranged to engage the said trip; a governor; connections between said governor and said shaft for rocking the latter from the former to cause said finger to press against and actuate said trip; a secondary trip-actuating device; and means for operating the last-named device.

3. In an engine controlling apparatus, the combination of a rocking, angular trip; a primary trip-actuating device associated 95 with one arm of the trip and comprising a rock shaft having a finger arranged to engage said arm; a governor; connections between said governor and said shaft for operating the latter from the former; a secondary trip-actuating device associated with the other arm of said trip and comprising a member having a hinged section arranged to engage said other arm; and means for moving said section into such engagement.

4. In an engine controlling apparatus, the combination of a pair of trips; a normally-operative, secondary trip-actuating device associated with each trip; means for operating said devices; a normally-inoperative, primary trip-actuating device associated with one of said trips; a governor; and connections between the governor and the primary trip-actuating device for operating the latter when the speed of the former becomes excessive.

5. The combination, with a mechanism for controlling hoisting engines, and power-operated means for actuating the same; of a pair of devices for controlling the operation of said actuating means; a trip associated with each controlling device; a traveling member for automatically actuating said trips at either end of its travel; and mechanism for automatically operating one of said trips at any intermediate point in the travel of said member in either direction when the speed of the engine becomes excessive.

6. In an engine controlling apparatus, the

- combination of a trip; a pair of rock shafts one of which is provided with a member arranged to engage and actuate the trip; a crank arm secured to said shaft; a pair of 5 crank arms secured to the other shaft; a governor; a lever controlled by said governor and connected to one of the second-named arms for rocking the second-named shaft from the governor; and a link connection 10 between the other second-named arm and the first-named arm for causing both shafts to move in unison.
7. In an engine controlling apparatus, the combination of a pair of trips; a trip-actuating device associated with each trip; a movable member for operating said devices alternately; a rock shaft; means for operating said shaft; and connections between said shaft and both devices for moving the 15 latter in unison when the former is operated.
8. In an engine controlling apparatus, the combination of a pair of trips; a trip-actuating device associated with each trip; a member arranged to travel between said devices for operating the same alternately; a rock shaft; means for operating said shaft; and connections between said shaft and both devices for moving the latter simultaneously toward the traveling member when 20 said shaft is operated.
9. In an engine controlling apparatus, the combination of a pair of trips; a secondary trip-actuating device associated with each trip; a primary trip-actuating device associated with one of said trips; a member for operating the secondary devices arranged to travel between the same; a rock shaft; means for operating said shaft; means operated by said shaft for operating the primary 25 actuating device; and connections between said shaft and both secondary actuating devices for moving the latter in unison toward said traveling member.
10. In an engine controlling apparatus, the combination of a pair of trips; a secondary trip-actuating device associated with each trip; a primary trip-actuating device associated with one of said trips; a member for operating the secondary 30 devices arranged to travel between the same; a rock shaft; a governor; connections between said governor and said shaft for op-

erating the latter from the former; means operated by said shaft for operating the primary actuating device; and connections 55 between said shaft and both secondary actuating devices for moving the latter in unison toward said traveling member.

11. In an engine controlling apparatus, the combination, with a trip; of an actuating device therefor having at one end a plurality of steps of different lengths; a member for operating said device arranged to travel in front of said end and normally co-operative with the longest step only; and 60 means for moving said device bodily toward said member under predetermined conditions, to bring a second step into position for co-operation therewith.

12. In an engine controlling apparatus, 70 the combination, with a trip; of an actuating device therefor having at one end a plurality of steps of different lengths; a member for operating said device arranged to travel in front of said end and normally co-operative with the longest step only; a governor; and means controlled by said governor for moving said device bodily toward 75 said member under predetermined conditions, to bring a second step into position 80 for co-operation therewith.

13. In an engine controlling apparatus, the combination of a pair of trips; a primary trip-actuating device associated with one trip; a secondary trip-actuating device 85 associated with the other trip and having at one end a plurality of steps of different lengths; a member for operating the secondary actuating device arranged to normally co-operate with the longest step only of 90 said end; means for operating the primary actuating means; and means operable by the last-named means during its operation for moving said secondary actuating means toward said member to bring a second step 95 thereon into position to co-operate with said member.

In testimony whereof I have hereunto set my hand in presence of two subscribing witnesses.

CLARENCE R. WELCH.
